UNITED STATES PATENT OFFICE.

JOHN C. BRACKETT, OF MILWAUKEE, WISCONSIN, ASSIGNOR TO INGERSOLL-RAND COMPANY, OF JERSEY CITY, NEW JERSEY, A CORPORATION OF NEW JERSEY.

LOADING MACHINE.

Application filed February 9, 1922. Serial No. 535,349.

To all whom it may concern:

Be it known that I, JOHN C. BRACKETT, a citizen of the United States, and a resident of Milwaukee, county of Milwaukee, and 5 State of Wisconsin, have invented a certain Loading Machine, of which the following is a specification, accompanied by drawings.

This invention relates to shoveling and loading machines, but more particularly to 10 the type of machine disclosed in the co-pending application of Bruce A. Middlemiss, Serial No. 143,116, filed January 18, 1917, in which a scoop or shovel is actuated through a cycle of digging and discharging 15 movements comprising a forward digging and filling movement, a lifting and swinging movement back over the machine to discharge the material and a return movement to the front of the machine for the beginning 20 of the next cycle. The present invention is in some respects an improvement upon the machine disclosed in the said co-pending application with added features although the principles of operation remain 25 substantially the same.

One object of the present invention is to enable the substantially horizontal lineal thrust or crowding movement of the digging mechanism to be converted into an upward 30 slicing stroke for the scoop which better fills the scoop, and loosens the material in the pile in readiness for the next digging and filling stroke.

Other objects are to enable both the advancing and the horizontal swinging movements of the machine to be controlled from one manually operated device, to secure a self-locking or non-reversible advancing mechanism, which will automatically lock 40 the machine against skidding away from the pile, and provide simple and compact mechanism for swinging or turning the frame of the machine from side to side on its truck or carriage.

45. Further objects of the invention will hereinafter appear, and the invention is shown in one of its preferred forms in the accompanying drawings, in which,

Figure 1 is a side elevation of a machine 50 embodying the invention,

Figure 2 is a top plan view of the machine,

Figure 3 is a rear end elevation of the machine,

Figure 4 is a detail transverse sectional elevation taken through the advancing and swinging motors on the line 4—4 of Figure 1, looking in the direction of the arrows.

Figure 5 is a longitudinal sectional elevation of the machine on the line 5—5 of Figure 2 looking in the direction of the arrows,

Figure 6 is a detail longitudinal sectional elevation taken through the cylinder and scoop, showing the scoop at the end of its advancing or crowded movement,

Figure 7 is a similar view showing the scoop in the position it assumes after the initial withdrawal and lifting movement,

Figure 8 is a similar view showing the digging mechanism and scoop in discharged position,

Figure 9 is a horizontal sectional plan view taken through the main cylinder on the line 9—9 of Figure 1,

Figure 10 is a view similar to Figure 9, with some of the parts in a different position;

Figure 11 is a detail side elevation partly in longitudinal section, showing the traction chain, and

Figure 12 is a detail top plan view of the truck with parts of the frame of the machine broken away showing the operation of the cable swinging the frame from side to side on the truck.

Referring to the drawings, a main frame A is mounted on the truck B having wheels C traveling on the rails D. A swinging unit including the shovel or scoop E and power mechanism, preferably in the form of a fluid pressure cylinder F, is pivotally mounted for swinging movement on the frame A, as by means of the cylinder trunnions G in the trunnion caps H. The cylinder is provided with a reciprocating piston J having a piston rod K, to the outer end of which a cross head L is connected in any suitable manner. A transverse scoop shaft O extends through the cross head, and the upper or back portion of the scoop E is pivotally mounted on the shaft O, as by means of the eyes P forming hinges.

Side arms Q are pivoted at each side of the main frame A on a transverse shaft R, and side arm links S are pivotally connected to the side arms Q as by means of the pins T at one end, the other ends of the side arm links S being formed with the slots U en-

gaging the transverse shaft O, so that the side arm links S have a given amount of play on said shaft. The side arms Q are formed with bifurcated ends V projecting beyond the pivot pins T, and hardened circular bearing pieces W are held within said ends V as by means of the rivets X. The side arm links S are preferably provided with hollowed portions Y with which the bearing pieces W are adapted to cooperate in certain positions of the actuating mechanism.

Tilting levers Z are pivoted to the lower portion of the cross head L on the transverse shaft a and the lower ends of these tilting levers are connected to the back of the scoop by the scoop links b. The opposite ends of the tilting levers Z are respectively pivotally connected by means of the pins c to pairs of tilting lever links d, which in turn are pivoted to brackets e on the cylinder head f, as by means of the pivot pins g.

A suitable recoil mechanism is mounted on the cylinder and is in this instance indicated as a housing h containing a spring k and connected to a rearward portion of the cylinder by the link j, and pivot pin k'. A plunger o within the cylinder is provided with a plunger rod p pivotally connected to a forward portion of the cylinder. A dash-pot in the form of a cylinder q is pivoted to the main frame as by means of the pin r, and the piston rod s is pivotally connected by the pin s' to the member t of which the pivot pin k' forms a part, so that in the swinging movement of the cylinder, the dash-pot may have a pivotal movement. The function of the recoil check is not only to check and cushion the rearward movement of the swinging mechanism by striking on the stop u, but to impart an initial forward movement to the cylinder and its connected parts, so that the cylinder is carried forwardly past the vertical, due to the action of the spring k in the recoil check, as will be apparent. The function of the dash-pot q and its parts, is to check the downward swing of the swinging mechanism, which returns to digging position by gravity.

In the operation of the digging mechanism, so far described, let it be assumed that the scoop is in initial digging position, as shown in Figure 5, with the piston J retracted in the cylinder F. Suitable means, to be described, are provided for distributing motive fluid to the cylinder through the trunnions and let it be assumed, that motive fluid is supplied behind the piston J, forcing the piston outwardly to the position indicated in Figure 6, which is the end of the outward stroke. As the scoop moves outwardly, the tilting levers Z are rocked on their pivots a and tilt the scoop, so that the final position of the scoop at the end of the

outward stroke, is that indicated in Figure 6, having been carried from a position in which the bottom of the scoop is substantially horizontal or tilted slightly downward, as indicated in Figure 5, to the final 70 position at the end of the outward stroke, in which the bottom of the scoop is tilted upwardly in the pile of material. On this initial outward stroke, the scoop rotates about the scoop shaft O as a center, and the 75 lineal substantially horizontal thrust imparted to the scoop is converted into an upward slicing stroke which is an important feature of the device and facilitates digging and filling. 80

Motive fluid is then admitted to the forward end of the cylinder F, and during that portion of the rearward stroke of the piston indicated in Figure 7, a withdrawal movement is imparted to the scoop as well as an 85 initial lifting movement, which is a continuation of the withdrawal movement combined with the lifting movement, before the raising or final lifting movement back over the machine to the position indicated in Figure 8, for the discharge of the material from the scoop. As the piston F starts to move rearwardly, the first effect is to move the scoop shaft O from the outer to the inner ends of the slots U in the lifting lever links 95 S, so that the scoop is withdrawn substantially horizontally from the pile for a short distance, depending upon the length of the slots. This short withdrawal movement is beneficial in loosening the scoop in the pile. 100 The side arm links S are then swung rearwardly about the side arm pivot pins T until the hollow portions Y of the said links S take up against the bearing members W at the ends of the side arms Q as indicated in Figure 7. The cylinder F has also tilted slightly about the trunnions G, the combined effect upon the scoop being to lift it from the position indicated in Figure 6 to that indicated in Figure 7. This initial lift is 110 also shown in Figure 6 by the dotted portion of the scoop E, which indicates not only the initial lift but the withdrawal movement of the scoop. The initial withdrawal and lift is important, because a strong lifting 115 force is provided to back the scoop out of the muck pile and start it in motion. Thereafter sufficient force is applied to complete the lifting and discharge stroke without throwing the scoop up too violently. 120

As the piston J travels rearwardly in the cylinder F from the position indicated in Figure 7, to that indicated in Figure 8, the cylinder is rotated about its trunnions G, while the side arms and connected parts rotate about the side arm shaft R. When the cylinder reaches the end of its discharge stroke, it is tipped rearwardly slightly beyond the horizontal, and the recoil check abuts against the stop u so that the material 130

is jarred out of the scoop into any suitable hopper, container, conveyer or other apparatus with which the digging mechanism co-operates. The piston J has reached the end 5 of its rearward stroke and abuts against the back head *v* of the cylinder, so that no more work is done by the piston. In this final dumping or discharge position of the cylinder and scoop and connected parts, the relationship between the pivotal parts of the cylinder and the trunnions G, and the pivot 10 for the side arm links provided by the scoop shaft P, is such that the toggles formed by the side arms Q and the side arm links S are opened, and the side arms and links assume the positions indicated in dotted lines in Figure 8, in readiness for the forward and downward movement of the scoop. The recoil check H throws the cylinder forwardly 15 past the vertical and gravity carries the parts back to the initial position indicated in Figure 5, as set forth in the said co-pending application of Bruce A. Middlemiss.

I prefer to distribute motive fluid, preferably compressed air, to the cylinder F through the trunnions G of the cylinder, which are indicated in detail in Figures 9 and 10. The trunnions G as shown, are hollow, and bearing sleeves *w* are provided between the trunnions and the trunnion caps H. The hollow trunnions are provided with ports *x* communicating with the passages *y* and *z* leading to the forward and rearward ends of the cylinder F respectively, and these 20 trunnions also communicate with passages 2 and 3 in the trunnion caps H leading to the valve chest 4 with which the supply pipe 5 of motive fluid is connected. The passage 2 in one trunnion cap communicates with said 25 valve chest 4 through the passage 6 in the main frame and the passage 7 in the opposite trunnion cap. The exhaust from the valve chest communicates with the exhaust passage 8 in the main frame, leading to atmosphere. A slide valve 9 in the valve chest 4 is connected by a link 10 to a rocker arm 11 on a transverse shaft 12 provided with the hand lever 13. In Figure 9, the valve 9 is shown in position to admit motive fluid 30 through the trunnion G leading to the back end of the cylinder, so that the piston J will be actuated on its forward stroke and the front end of the cylinder will be exhausted to atmosphere through the other 35 trunnion, and through the passages connected with the exhaust 8. In Figure 10 the valve 9 has been shifted to admit motive fluid to the front end of the cylinder and the rearward end of the cylinder is exhausted to atmosphere, all as indicated by the arrows.

The truck B is advanced and retracted from the pile by means of a suitable engine 14 and the main frame is swung in a horizontal plane on the truck by means of an 40 other suitable engine 15 and in this instance,

both these engines are indicated more or less diagrammatically as engines of the square piston type, known as Dake engines, although any other suitable type may be used for the same purposes. A traction chain 16 45 is suitably anchored at its forward end by means of a stake 17 for instance, near the face of the drift in the mine, and this chain is carried rearwardly over a sprocket 18 on the driven shaft 19 of the motor 14. The chain passes under idlers 20 forming guide rollers and the rearward end of the chain is also preferably staked or otherwise fastened between the rails D. The truck is advanced or retracted along the chain 16 in 50 accordance with the direction of rotation of the motor 14. In practice the miner will force the scoop as deep as possible into the muck pile and then turn the air into the digging cylinder F for the digging and filling stroke. The advancing engine 14 has in the meantime reached the limit of its power to cause the scoop to penetrate the pile and the engine stops with the forces in the machine substantially in balance for the completion of the operating cycle.

Sliding rail clamps 21 hook underneath the inside flanges of the heads of the rails D and prevent the machine from lifting off the rails or otherwise becoming derailed. This 55 construction in conjunction with the diagonal thrust which occurs when the digging cylinder is operated at an angle to the track, crowds these inside clamps snugly against the flanges of the rails.

In order to afford provision for swinging the main frame A horizontally on the truck, the truck is provided with a forward segmental housing 22 in which bearing rollers 23 are mounted and the truck is also provided with a series of rearward turrets 24 comprising vertical rollers 25 and horizontal rollers 26. The main frame A bears on the forward bearing rollers 23 and is also provided with a guide or swinging segment 27 60 which bears on the vertical bearing rollers 25 of the turrets. The swinging segment 27 is also guided by the horizontal rollers 26 of the turrets. Plates 28 bolted to the truck, extend over the swinging segment 27 and hold it and the main frame A against vertical movement at the rearward end. The main frame A is provided with a transverse filler piece 29 and a plate 30 riveted to the frame at the forward end, and this plate 30 extends 65 underneath the flange 31 of the segmental housing 22 and holds down the forward end of the main frame A. A cable 32 is connected at one end to an eye bolt 33 fastened to one side of the forward end of the main frame A, as indicated in Figure 12 and this cable passes down through a guide 34, is then turned horizontally through an aperture 35 in a downwardly projecting portion of said guide, passes over a guide roller 36 70

on the truck and after several turns around the drum 37 of the swinging motor 15, is guided over a roller 38 on the truck, adjacent the drum, then over another roller 39 on the truck adjacent the roller 36 and through the guide 40 to the eye bolt 41 at the opposite side of the main frame from the eye bolt 33. According to the direction of rotation of the drum 37 the main frame will be 5 swung to the right or the left on the forward guide rollers 23 and the turrets. Such arrangement of the cable and drum permits the machine to be narrow while affording a 10 simple and compact cable mechanism for 15 swinging the main frame on the truck.

The distribution of motive fluid to the two motors 14 and 15 is controlled by a single handle 42 pinned to the jointed valve shaft 43, which extends through the motor valve 20 chests 44 and 45. By rocking the handle 42 and valve shaft 43, the slide valve 46 in the 25 chest 44 will be actuated through the agency of the finger 47. The socket 48 of the handle 42 affords sufficient clearance for the 30 end of the valve shaft 43 to also permit the handle 42 to be rocked in the axial plane 35 of the valve shaft about the end 49 of the downwardly extending handle projection 50 as a pivot, so that said shaft 43 will be moved longitudinally for actuating 40 the slide valve 51 in the valve chest 45, through the agency of the finger 52. The rounded end 49 of the projection 50 of the handle 42 is preferably guided by a plate 45 53 suitably secured to the frame of the motor 14.

Motive fluid is supplied to both motors as well as to the cylinder A of the machine through the main supply pipe 54 connecting 50 with the supply pipe 5 leading to the cylinder A and suitable connections are made from said pipe 54 to the valve chests 44 and 55 55. The motors 14 and 15 are shown diagrammatically in Figure 4 as conventional square piston motors of the Dake type, and need not be described in detail, except to indicate the principal parts. The cylinder cover or head 55 of the motor 14 is provided with the inlet passage 56, and the exhaust passages 57. The cylinder 58 is provided with the outer frame piston 59 and the inner piston 60 of the usual construction, reciprocating within the outer piston. The crank shaft 61 is connected to the inner 65 piston 60 by the crank pin 62 and rotation is imparted to the crank shaft by the movements of the outer and inner pistons. The crank shaft is formed with a worm 63 meshing with a wheel 64 on the motor shaft 19 carrying the sprocket 18 over which the traction chain passes.

The cylinder head or cover 66 of the motor 15 is provided with the inlet passages 67 and exhaust ports 68 and otherwise the construction of the motor 15 is substantially

similar to that of the motor 14 and drives the drum 37 for the swinging cable 32. Due to the worm and wheel, included in the gearing of the advancing cylinder, the gearing is non-reversible and self locking and 70 automatically locks the machine against skidding back away from the pile.

In the operation of the machine, let it be assumed that the traction chain 16 has been secured in position, and it is desired to advance the truck along the track to digging 75 position. The handle 42 will be rocked in order to rock the valve shaft 43 about its axis, for admitting motive fluid to the advancing motor 14, for causing said motor to 80 rotate the sprocket 18 in a direction to move the truck forwardly along the rails. Before starting the digging operations, it may be desirable to swing the main frame on the truck to one side or the other to the 85 most advantageous position for digging and for this purpose, the handle 42 is rocked about the pivot 49 in a direction to move the valve shaft 43 longitudinally which will admit motive fluid to the motor 15 and 90 cause said motor to drive the drum 37 and wind the cable 32, in the proper direction to swing the main frame on the forward guide rollers 23 and the vertical turret rollers 25 to the position desired. With the 95 digging mechanism in the position indicated in Figure 1, the handle 13 is then manipulated to admit motive fluid to the rearward end of the cylinder A which actuates the digging mechanism and scoop 100 through the cycle hereinbefore described. The scoop is first advanced or crowded into the muck pile from the position shown in Figure 1 to that indicated in Figure 6 and at the same time, the scoop is slightly tilted 105 by means of the tilting levers and tilting lever links. The lever 13 is then reversed to admit motive fluid to the forward end of the cylinder and exhaust the rearward end, so that the initial withdrawal movement is 110 imparted to the scoop, combined with an initial lift and the continued rearward movement of the piston F in the cylinder raises and swings the scoop to discharge 115 position, as indicated in Figure 8, after which the digging mechanism returns by gravity to the initial position indicated in Figure 1 ready for the next cycle.

I claim:

1. A loading machine comprising a frame, 120 a scoop, and vertically swinging means for causing the scoop to be moved through the following cycle of operations: first, a forward lineal substantially horizontal thrust converted into an upward slicing movement 125 by tilting the scoop, than an initial withdrawal and lift of the scoop followed by a continuous lift and swing of the scoop back over the machine to discharge position, and finally a downward and forward movement 130

of the scoop to initial position at the front of the frame for the beginning of the next succeeding cycle.

2. A loading machine, comprising a frame, a scoop, and vertically swinging means for causing the scoop to be moved through the following cycle of operations: first, thrusting the scoop lineally forward substantially horizontally and converting the said lineal thrust into an upward slicing movement of the scoop by tilting the scoop, then initially withdrawing and lifting the scoop and continuing to lift and swing the scoop back over the machine to discharge position, and permitting the scoop and operating mechanism to fall by gravity to the front of the machine for the start of the next cycle.

3. A loading machine comprising a frame, a reciprocating motor mounted to swing vertically on the frame, a scoop connected to a reciprocating part of said motor, side arms pivoted to the frame and side arm links connecting the side arms with the

scoop, and tilting levers connected to the scoop, whereby the scoop is tilted as it is thrust forward by the motor.

4. A loading machine comprising a frame, a reciprocating motor mounted to swing vertically on the frame, a scoop connected to a reciprocating part of the motor, side arms pivoted to the frame and side arm links connecting the side arms with the scoop, tilting lever links pivoted to a stationary part of the motor and tilting levers connecting the tilting lever links with the scoop, whereby the scoop is tilted as it is thrust forward by the motor.

5. In a loading machine, the combination of a frame, a motor, hollow trunnions for said motor mounted in said frame, trunnion caps over the trunnions containing motive fluid passages and means for distributing motive fluid to said motor through the trunnions and trunnion caps.

In testimony whereof I have signed this specification.

JOHN C. BRACKETT.
